CLAIM

The ornamental design for a bowl with a base, as shown and described.

DESCRIPTION

FIG. 1 is a front, top perspective view of a bowl with a base, showing our new design;

FIG. 2 is a back, top perspective view of the bowl with a base of FIG. 1;

FIG. 3 is a left side, top perspective view of the bowl with a base of FIG. 1;

FIG. 4 is a right side, top perspective view of the bowl with a base of FIG. 1;

FIG. 5 is a top view of the bowl with a base of FIG. 1;

FIG. 6 is a cross-sectional view of the bowl with a base along the 6-6 line shown in FIG. 5;

FIG. 7 is a bottom view of the bowl with a base of FIG. 1;

FIG. 8 is a right side elevation view of the bowl with a base of FIG. 1;

FIG. 9 is a left side elevation view of the bowl with a base of FIG. 1;

FIG. 10 is a front side elevation view of the bowl with a base of FIG. 1;

FIG. 11 is a back side elevation view of the bowl with a base of FIG. 1; and,

FIG. 12 is a bottom perspective view of the bowl with a base of FIG. 1.

The broken line cross section marker in FIG. 5 forms no part of the claim.

1 Claim, 12 Drawing Sheets
